TERA & E. KING,

Fence Post,

No. 20,352.

Patented May 25, 1858.

UNITED STATES PATENT OFFICE.

T. E. KING, A. KING, AND E. KING, OF CHERRY VALLEY, OHIO.

IRON GATE OR FENCE POST.

Specification of Letters Patent No. 20,352, dated May 25, 1858.

To all whom it may concern:

Be it known that we, T. E. KING, ALEX. KING, and EDWIN KING, of Cherry Valley, in the county of Ashtabula and State of Ohio, have invented new and useful Improvements in Fence-Posts; and we do hereby declare that the following is a full and complete description of the construction and operation of the same, reference being had 10 to the accompanying drawings, making part of this specification, in which—

Figure 1 is a side view; Fig. 2 is a view of a post turned one quarter around, that is, the post is viewed in the direction of the 15 line of the fence; Fig. 3 is a view of the several parts detached, that make up the post, and Fig. 4 is a horizontal section, showing the manner of forming a right angle in the line of fence.

20 The nature of our invention consists in the construction of a fence post of cast iron or other suitable material, of such structure in its several parts that the post can be put together or taken apart at pleasure, and by 25 this means to introduce the rails or panels without the use of pins or bolts, or to remove them at pleasure, the several parts of the post forming all the fastening needed, the form thereof being also such that the fence 30 can be turned at right angles without any change in the form of the post. The posts are also so constructed that the rails or boards of which the fence may be constructed can be secured at any desired point of 35 elevation, and there firmly held without pins, nails or bolts. Hinges for gates may also be secured in the same manner to the posts as are the rails.

40 A, A, Fig. 1, represent the main body of the post after the several parts have been put together.

B, B, B, in Figs. 2 and 3, represent the arms which serve to lock the two parts of the post together.

45 C, C, C, represent the keys or wedges that secure the parts in place.

D, D, Figs. 1 and 2, represent that part of the hinge attached to the post, and E, E, that part of the hinge that is attached to the 50 gate.

F, F, F, Fig. 1, represent sections of rails secured to the post, in the manner herein-after set forth.

The main body of the post is composed of 55 two parts, as seen in Figs. 2 and 3. G represents that part to which the base H, and

cap I, are connected, and which constitute one piece of casting. This part G, forms the front side of the post. The opposite, or back side of the post is shown at K, Figs. 2 60 and 3. The back side is also shown in Fig. 1. When both parts are put together, they form an octagon figure as seen in Fig. 4. The two inner edges of the two halves of the post are furnished with teeth or notches a, 65 a, which teeth become embedded in the sides of the rail when the two parts are keyed together, and in this manner the rails are kept in place.

That portion of the hinge which is secured to the post, and seen at D, D, is composed of a bar which passes between the two parts of the post G and K, this bar having lugs e, e, upon each side as seen in section in Fig. 1, which lugs set into the notches a, a, 70 Figs. 2 and 3, and thus hold that part of the hinge firmly when the two parts G and K, are keyed together. The pin e, e, rising from the outer end of the hinge D, forms 75 the point of articulation for the other part 80 of the hinge.

That portion of the hinge which is attached to the gate is shown at E and E' Fig. 1. This consists of a socket head, of cast iron, which fits upon the pin e, e, Figs. 85 1 and 2. The rail of the gate enters this socket and is secured by a pin or bolt passing through the wings of the socket and rail, as seen at E', Fig. 1.

The lower end of that part of the post marked K, in Figs. 2 and 3, has wings i, i, Fig. 3, stretching across the bottom, leaving however a slot i', into which the T head bolt or stud o, Fig. 3, enters, for the purpose of securing the upright part K, to the base H. 95

In setting up this fence the base H, should be attached to a flat stone, partially embedded in the ground, by a bolt in the center of the base.

Upon the inside of the upright part G, a 100 rib extends from top to bottom, seen at m, Fig. 3, shown also at m, Fig. 4, in cross section. This rib serves both to strengthen the post and form a support against which the end of the rails rest in turning the fence 105 at right angles, as seen L, L, Fig. 4.

The cap I, may be cast with the body G, and base H, or made in a separate piece and of any desired form, and secured to the top of the parts G, and K, in any convenient 110 manner.

The arms B, B, B, are cast rigidly with

the piece G, the projecting end being furnished with a head, which passes through corresponding openings in the part K, the head of the arm B, passing a sufficient distance to admit the introduction of the key C, behind the shoulder of the head of the arm B. The keys are U shaped, as seen in Fig. 3. The manner of their insertion, is shown in Fig. 2.

- 10 In setting up a fence with our improved post, the rails or boards should be cut of proper length and the ends thereof brought to a uniform thickness. That part of the posts marked G, should then be properly secured to their respective foundations and otherwise suitably arranged, and the part K then placed in position. The boards or panels are then introduced between the two parts of the post and placed at the proper 15 distance apart and the keys C, C, C, introduced, and driven snugly home, and this grips the boards firmly between the serrated or toothed edges of the post and holds them snugly in place. In making picket 20 fence two rails only are needed, and these are held in the same way as above described.

The pickets are nailed in the usual manner. In this case the panels thus formed can be detached from the posts and replaced again at pleasure. In turning a corner the rails 30 or panel ends meet at the rib m, as seen in Fig. 4.

What we claim as our invention, and desire to secure by Letters Patent, is

1. A fence post, composed of the parts G and K, provided with toothed or serrated edges a, a, arms B, and keys C, and in combination therewith the wings i, i, and stud o, when constructed and arranged substantially in the manner and for the purpose 35 specified.

2. We also claim the manner of securing the gate hinges D, by means of the lugs c, c, and notches a, a, the same being held in place by the keys C, as described.

T. E. KING.
ALEX. KING.
EDWIN KING.
